CLAIM

The ornamental design for a smartphone case with flip-out solar panel, as shown and described.

DESCRIPTION

FIG. 1 is a perspective view of a smartphone case with flip-out solar panel showing the new design in the closed position;

FIG. 2 perspective view thereof in the open position;

FIG. 3 is a rear view thereof in the closed position;

FIG. 4 is a rear view thereof in the open position;

FIG. 5 is a front view thereof in the closed position;

FIG. 6 is a front view thereof in the open position;

FIG. 7 is a right view thereof in the closed position;

FIG. 8 is a right view thereof in the open position;

FIG. 9 is a left view thereof in the closed position;

FIG. 10 is a left view thereof in the open position;

FIG. 11 is a bottom view thereof in the closed position;

FIG. 12 is a bottom view thereof in the closed position; and,

FIG. 13 is a top view thereof.

The broken line portions of the drawings are included to show portions of the article that form no part of the claimed design.

1 Claim, 13 Drawing Sheets
